DESIGN FOR A RADIATOR GRILLE COVER

Harry E. Kaemmer, Fremont, Ohio

Application August 23, 1935, Serial No. 58,254

Term of patent 7 years

To all whom it may concern:

Be it known that I, Harry E. Kaemmer, a citizen of the United States and resident of Fremont, in the county of Sandusky and State of Ohio, have invented a new, original, and ornamental Design for a Radiator Grille Cover, of which the following is a specification, reference being had to the accompanying drawing, forming a part thereof.

The figure is a front elevational view of a radiator grille cover, with flap covered openings, embodying my new design, one flap being in open and the other in closed position. The dotted lines indicate stitching.

I claim:

The ornamental design for a radiator grille cover substantially as shown and described.

In testimony whereof I have hereunto signed my name to this specification.

HARRY E. KAEMMER.
